UNITED STATES PATENT OFFICE.

JOHN E. CONZELMAN, OF ST. LOUIS, MISSOURI, ASSIGNOR TO UNIT CONSTRUCTION COMPANY, OF ST. LOUIS, MISSOURI, A CORPORATION OF DELAWARE.

DOUBLE-WALL CONSTRUCTION.

1,079,111.

Specification of Letters Patent. Patented Nov. 18, 1913.

Application filed November 9, 1911. Serial No. 659,298.

To all whom it may concern:

Be it known that I, JOHN E. CONZELMAN, a citizen of the United States, residing at the city of St. Louis, State of Missouri, have 5 invented certain new and useful Improvements in Double-Wall Constructions, of which the following is a specification.

This invention relates to concrete building structures and has particular reference 10 to a construction in which concrete slabs and columns are united to form a wall having an air-space therein and being particularly adapted for cold storage plants, residences, and the like.

15 In the construction of concrete buildings, it is essential that secure and durable junctions be made between the columns and the wall slabs of the structure.

It is an object of this invention to provide 20 a structure of concrete building elements, which coöperate and are interengaged to form a rigid, secure and lasting combination of elements.

It is, also, an object to provide a concrete 25 building structure in which the general construction of the coöoperating uprights and wall slabs is generally improved.

With these objects in view, this invention 30 consists of the novel features of construction and arrangement of parts, as will be hereinafter more fully described and pointed out in the claims.

In the accompanying drawings forming 35 part of this specification, in which like numbers of reference denote like parts wherever they occur, Figure 1 is a horizontal sectional view of a wall constructed in accordance with the present invention; and Fig. 2 is a side elevation thereof.

40 In accordance with the invention a double wall is constructed of a plurality of panels formed of slabs 18 and 2. The slabs 18 of each panel are joined to the slabs of the next panel by means of lapped joints. Each 45 slab 18 is preferably molded with a rectangular configuration, and each end thereof is provided with an extension 19. Each extension 19 is offset from its slab 18, preferably a distance substantially equal to the 50 thickness of the adjoining slab 18 of the next panel, in order to overlap and, also, to fit closely to part of the face of said adjoining slab. The extension 19 on one end 55 of said slab 18 is located on the opposite side thereof from which the extension 19 on

the other end of said slab is located. In order to join two adjoining slabs 18 of adjacent panels, one is placed in alignment with the other, so the extension 19 on an end of the former overlaps part of the face 60 of the latter, and the extension 19 on an end of the latter overlaps part of the face of the former, said slabs being spaced apart sufficiently to leave a space 20 between the ends of said slabs and the inner faces of said 65 extensions. The extensions 19 are preferably formed with equal widths and are located directly opposite each other, so that the wall has the appearance of having columns between the panels. The space 20 is 70 filled with grout or wet concrete, which sets integrally with the extensions 19 and, also, the ends of slabs 18. When the slabs 18 are placed one on top of another, in order to form a panel of the wall, the extensions 19 75 at one side of the panel register in vertical alignment, as do the extensions 19 at the other side of the panel. The slabs 2 are placed one on top of another between the extensions 19 on one side of the wall, so that 80 the flanges 3 on said slabs 2 fit against the faces of slabs 18, whereby the air-space 6 is left between said slabs 2 and 18. The ends of slabs 2 fit against the sides of said extensions 19 and the faces of said slabs 18 85 register in substantially the same vertical plane with the faces of said extension.

The double wall constructed as hereinabove described is light in weight and renders the room inclosed thereby moisture 90 proof.

I claim:

1. In a double wall construction, a panel consisting of a double wall of slabs, each slab of one wall of said panel having extensions formed integrally with the ends thereof, said extensions being offset from opposite sides of said slab to overlap similar slabs in each panel adjacent thereto, each slab of the other wall of said panel being 100 arranged to fit between the extensions at the sides of said panel and having flanges that fit against a face of said first-mentioned slab, thereby to leave an air-space between said walls, the exposed faces of each slab of said other wall being substantially flush with the exposed faces of each extension adjacent thereto.

2. In a double wall construction, a panel consisting of a double wall of slabs, each 110

slab of one wall of said panel having extensions formed integrally with the ends thereof, said extensions being offset from opposite sides of said slab to overlap similar slabs in each panel adjacent thereto, each slab of the other wall of said panel being arranged to fit between the extensions at the sides of said panel and having flanges that fit against a face of said first-mentioned slab thereby to leave an air-space between said walls, the exposed faces of each slab of said other wall being substantially flush with the exposed faces of each extension adjacent thereto, there being a space between each end of said first-mentioned slab and the end of a similar slab of each panel adjacent thereto and, also, between the inner faces of the extensions borne thereby, and a concrete filler for said last-mentioned space adapted to set integrally with the ends of the slabs and extensions surrounding same.

3. In a wall, a series of slabs each having an offset extension at each end, one of the extensions of each slab being located at the front face thereof and having its rear face registering in substantially the plane of the front face of said slab, and the other extension being located at the rear face thereof, and having its front face registering in substantially the plane of the rear face of said slab, the rear face of one end of one slab engaging the front face of the adjacent slab extension and the rear face of said extension engaging the front face of the slab having said extension, there being a space between the ends of said adjacent slabs, and a concrete filler in said space.

4. In a wall, a series of slabs each having an offset extension at one end, the rear face of said extension of one slab registering in substantially the plane of the front face of said slab and overlapping and engaging the front face of the adjoining end of an adjacent slab, and a second series of slabs arranged between the outer face of the end of an extension of one of the first named slabs and the inner end face of the extension of an adjacent one of said first named slabs.

5. In a wall, a series of slabs each having an offset extension at each end that project beyond the side faces thereof, said slabs being arranged so that the inner face of each extension registers in substantially the same plane throughout with, and overlaps and engages the adjacent side face of the adjacent slab, the extensions of a pair of slabs being located substantially opposite to one

another and in alinement to provide a column on each of the side faces of the slabs.

6. In a wall, a series of slabs each having an offset extension at each end that project beyond the side faces thereof, said slabs being arranged so that the inner face of each extension registers in substantially the same plane throughout with, and overlaps and engages the adjacent side face of the adjacent slab, the extensions of a pair of slabs being located substantially opposite to one another and in alinement to provide a column on each of the side faces of the slabs, the adjacent ends of the slabs being spaced apart and said extensions extending across said space and closing same to form a vertical space, which space is closed at its ends by the outer end faces of the slabs and at its sides by the inner side faces of the extensions of said slab ends, the end walls which define said space being formed by the adjacent ends of the slabs and the side walls which define said space being formed by the inner faces of said extensions.

7. In a wall, a series of aligned slabs, one slab having a projection on one end that registers in the same plane throughout with, and overlaps and engages the exposed rear side face of the adjacent slab at said end thereof and further having a projection on its opposite end which registers in the same plane throughout with, and overlaps and engages the exposed front side face of the adjacent slab at said opposite end thereof, the projections of said slab extending beyond the rear and front side faces thereof to act as columns which are located on the opposite side faces of the wall.

8. In a wall, a series of slabs each having an offset extension at each end that project beyond the side faces thereof, said slabs being arranged so that the inner face of each extension overlaps and engages the adjacent side face of the adjacent slab, the extensions of a pair of slabs being located substantially opposite to one another and in alinement to provide a column on each of the side faces of the slabs, and a second series of slabs on one side of the wall arranged between the end faces of the columns on said side of the wall.

In testimony whereof I hereunto affix my signature in the presence of two witnesses.

JOHN E. CONZELMAN.
